UNITED STATES PATENT OFFICE.

WILLIAM WATTS, OF LOUISVILLE, KENTUCKY.

BUNCHER AND BANDER.

1,104,155.

Specification of Letters Patent. Patented July 21, 1914.

Application filed March 23, 1914. Serial No. 828,628.

To all whom it may concern:

Be it known that I, WILLIAM WATTS, a subject of the King of Great Britain, residing at the city of Louisville, in the county of Jefferson and State of Kentucky, have invented a new and useful Improvement in Bunchers and Banders, of which the following is a specification.

This invention relates to bunchers and banders of the class used in printing establishments and binderies holding quantities of sheets, cards or pamphlets in a compressed state while they are encircled with a band, or other securing means for retaining the package in a compacted state.

An object of the invention is to provide a device of the character stated that will be economical in construction and efficient in service.

With the foregoing objects in view the invention consists of the novel arrangement of parts illustrated in the accompanying drawings which form a part of this specification, wherein is set forth an embodiment of the invention, but it is to be understood that such changes and modifications in size, shape and of minor details may be made as come within the scope of the appended claims.

Referring to the drawings wherein like reference characters designate corresponding parts in the several views; Figure 1, is a side elevation, with a part broken away; Fig. 2, a top plan view; Fig. 3, a rear elevation; Fig. 4, a transverse section on line X—X of Fig. 1; Fig. 5, a transverse section on line Y—Y of Fig. 1; Fig. 6, a perspective of the sliding head; Fig. 7, a perspective of the adjustable head.

Referring to the drawings, 1 designates a bed supported by legs 2. On each side of the bed are raised portions 3 forming guide rails. At the rear end of the bed, on each side, within the rails 3, standards 4 are erected, being secured in place by suitable means, such as 5, that pass up through the bed and engage in the standards. From the top of each of the standards an arm 6 extends forward in a plane parallel with the bed. A head 7, positioned for reciprocal movement between the guide rails and the overhanging arms 6, comprises a base-plate 8, and vertical members 9. A head 10 comprising a base-plate 11 and vertical members 12, is adjustably secured on the guide rails by suitable means, such as bolts 13 which

pass through slots 14, in the bed, and up through the vertical members 12, and are provided on the upper end with nuts 15, which furnish a readily accessible means of releasing and setting the head, in desired adjustments. Plates 16, secured to projections 17, rising from the bed, extend longitudinally of the bed between the divided portion of the heads 7 and 10, and lie over the base-plates of the heads. On the forward end of each plate is an upturned portion 18, that serves as a stop for bands placed on the plates. A shaft 19, mounted transversely below the bed, bears on the ends thereof vertical arms 20, in the upper ends of which are pins 21 that engage in slots 22 in the sides of the head 7. Extending forward from the shaft 19 is an arm 23, which is connected by a depending rod 24 to a foot lever 25. The arrangement being such that pressure exerted on the foot lever will advance the head 7. Means are provided for retracting the head 7, and maintaining it normally in a retracted position, such means may be springs 26, connected respectively to the head and the standards 4; though any other suitable means may be used.

To use the machine a quantity of bands, as 31, of suitable material, such as paper, are placed on the plates 16, between the divided parts of the heads, said parts of the heads being spaced apart a distance sufficient to receive the maximum width of band to be used. To use bands of less width, the distance between the vertical portions of the heads may be reduced by attaching plates 29, of varying widths, to the faces of the heads. The sides of the bands are kept in alinement by said heads, or the plates, while the ends are kept in alinement by the upturned ends 18 of the plates 16, on which the bands are arranged. The head 10 is then adjusted at such distance from the head 7 that the space between them will just admit the number of the product it is desired to have in each package. A bunch of sheets as 32, is then placed between the heads, resting on the bands, and straightened by being butted against a plate 30, secured on the side of the bed. The bunch of sheets is received between the heads in their normal bulk, then by exerting pressure on the foot lever the head 7 is advanced compressing the bunch of sheets to a lessened bulk. One end of a band, say the rear end, is then brought up over the bunch and

turned down thereon, the forward end of the band is then brought up and turned down, on that portion already positioned, and secured in place by suitable means, such as an adhesive applied with a brush, by means of gum previously applied to the forward end of the band, or by the use of a gummed wafer, or strip of gummed paper, which is placed across the juncture of the overlapping end of the band with the main body thereof. At 33 is shown a container adapted to hold a roll of paper 34, gummed on one side, this strip of paper passes between rolls 35 and 36, the roll 36 being adapted to moisten the gum on the strip. Portions of any desired length may be severed from the strip 34 and utilized to secure a band about a bunch.

As illustrated the device is provided with relatively short legs 2 necessitating the use of a stand 37, to support it at a suitable elevation for operation, but it is evident that the legs may be extended and the stand dispensed with.

It is thought that the construction, operation and manifold advantages of my invention may be clearly understood from the foregoing without more extended description.

Having thus described my invention so that any one versed in the art pertaining thereto may make and use the same, I claim:

1. In a machine of the class described, a bed, guide rails on each side thereof, standards erected on the rear end of said bed, arms extending forward from said standards in a plane parallel with the bed, a mov-

able head positioned between said arms and said guide rails, an adjustable head positioned on the bed forward of said movable head, means for advancing said movable head and means for retracting and normally holding said movable head retracted. 46

2. In a machine of the class described, a bed, guide rails thereon, standards erected at the rear end of the bed, arms extending forward from said standards in a plane parallel with said guide rails, a movable head positioned between said arms and said rails, a head adjustably secured on said rails by means of bolts passing through slots in said bed and up through said head, a shaft mounted transversely beneath the bed, arms on the ends of said shaft provided with pins adapted to engage with said movable head, a foot-lever, connections between said lever and said shaft, and means for normally holding said movable head in a retracted position. 45 50 55 60

3. In a machine of the class described, a bed, standards erected thereon, overhanging arms on said standards, a movable head between said arms and the bed, an adjustable head positioned on the bed, a transverse shaft, vertical arms on said shaft, pins in said arms engaged in said movable head, a foot lever, a connection between said lever and said shaft, and means for normally holding said parts in an inoperative position. 65 70

WILLIAM WATTS.
